Mayer, Marfield & Watson

ATTORNEYS.

UNITED STATES PATENT OFFICE

SAMUEL SEGAL, OF NEW YORK, N. Y.

LOCK MOUNTING

Application filed August 9, 1927. Serial No. 211,648.

This invention relates to a mounting member for locks, and particularly rim type locks.

It is an object of the invention to provide a member of this type, and by means of which the bolt of the lock may be aligned with the keeper without forming a recess in the jamb; the present invention also contemplating a mounting member by means of which variations in alignment may be compensated for.

10 It is a further object of the invention to provide a device of this character which may be readily and economically manufactured and which will be rugged in construction.

Other objects of the invention will in part 15 be obvious and will in part appear hereinafter.

The invention accordingly comprises an article of manufacture possessing the features, properties, and the relation of elements 20 which will be exemplified in the article hereinafter described and the scope of the application of which will be indicated in the claims.

For a fuller understanding of the nature 25 and objects of the invention reference should be had to the following detailed description taken in connection with the accompanying drawing, in which:

Figure 1 is a side elevation of a lock mounting embodying the present invention;

Fig. 2 is a sectional plan view taken along the lines 2—2 and in the direction of the arrows of Fig. 3; and

Fig. 3 is an end view of the mounting.

35 In these views the body of the mounting is shown as including a substantially U-shaped portion 5 embracing a body, which as in Fig. 2 is substantially T-shaped in cross-section. It will be noted further in 40 this figure that the shank 6 of this portion is disposed nearer one side edge thereof than the other. As a consequence, on one side of the mounting a comparatively shallow recess 7 is provided, and on the other side a 45 comparatively deep recess 8 is furnished. The arms of the portion 5 are joined by a web 9, the outer edge of which may be thickened as at 10; it being observed—referring to Fig. 3—that adjacent its upper and lower 50 ends the web may be recessed at 11 to provide

at these points a space having a depth equal to the depth of the recess 8.

It will be understood that the present mounting has been shown and described as having such a shape as is desirable for the 55 mounting of a lock having a corresponding outline. It will be appreciated, however, that the shape of the mounting member may be varied in numerous respects to conform to the outline of the lock which is to be mounted. 60

Thus, with reference to the specific embodiment illustrated, if it is found that the keeper of a rim type lock does not align properly with the lock bolt, which difficulty normally would necessitate the recessing of the door 65 jamb to accommodate the keeper, the mounting is applied to the face of the door, and the lock is, in turn, positioned beyond the outer edge of the mounting member. To secure the parts in position it will be apparent that the 70 usual screws or bolts which fasten the lock case to the door may be utilized, and to this end, the web 9 is formed with openings 12 for the passage of these members. The lock case will fit snugly against the mounting and 75 its edge will bear against the outermost edge of the shank 6.

Obviously, by means of the present invention, if it is found that with the lock casing extending into the recess 8 the bolt does not 80 align with the keeper secured to the door jamb, the mounting member may be reversed so that the lock casing extends into the shallower recess 7; it being thereupon apparent that the bolt, when projected, will extend in 85 proper line with the keeper recess.

Thus, among others, the objects of this invention have been accomplished, and since certain changes may be made in the above article and different embodiments of the invention could be made without departing from the scope thereof, it is intended that all matter contained in the above description or shown in the accompanying drawing shall be 90 interpreted as illustrative and not in a limiting sense.

It is also to be understood that the following claims are intended to cover all of the generic and specific features of the invention herein described, and all statements of the 95 100

scope of the invention which as a matter of language might be said to fall therebetween.

Having described my invention, what I claim as new and desire to secure by Letters Patent is:

- 5 1. A mounting member to be interposed between a lock casing and a support therefor, said member including a body formed with recesses of different depths in its opposite faces and within either of which the lock casing is to seat.
- 10 2. A mounting member to be interposed between a lock casing and a support therefor, said member including a body T-shaped in cross section, the shank of said T being disposed nearer one of its side edges than the other side edge thereof.
- 15 3. A mounting member to be interposed between a lock casing and a support therefor, said member including a body presenting a pair of arms and a web portion extending between said arms and being of a thickness less than the thickness of said body.
- 20 4. A mounting member to be interposed between a lock casing and a support therefor, said member including a body presenting a pair of arms and a web portion extending between said arms and being of a thickness less than the thickness of said body, the edge of
- 25 30 said web being relatively thickened, and the body thereof being formed with openings for the passage of fastening elements.
- 35 5. A mounting member to be interposed between a lock casing and a support therefor, said member including a body presenting a pair of arms and a web portion extending between said arms and being of a thickness less than the thickness of said body, the edge of
- 40 45 said web being relatively thickened, and being reduced adjacent its ends to a thickness substantially equal to that of the web body.
- 50 6. A lock mounting including a body shaped to conform to the lock casing which it is to mount, said body presenting a pair of spaced arms, and a web of material integral with and extending between said arms and in a plane intermediate the side faces thereof, said web being formed with openings for the passage of fastening elements extending from the lock casing which said member is to mount.

In testimony whereof I affix my signature.
SAMUEL SEGAL.
